UNITED STATES PATENT OFFICE.

EUGENE E. ANDERSON, OF KANSAS CITY, MISSOURI.

ELECTRIC HEATER.

Application filed March 2, 1925. Serial No. 12,738.

This invention relates to electric heaters of the particular class in which a reflector and a heating element are so associated that the stream lines or heat rays from the heating element impinge upon the reflector and are reflected outwardly in the form of a beam of heat, the cross sectional area and density of the so called beam being governed by the form of the reflector.

5 Prior to my invention heaters have been used in which the resistance wire for the heating element was wound around a spool. If the spool was arranged horizontally only half of the effective part of the heating element was presented to the reflector. Consequently, only fifty per cent of the heat generated was reflected heat.

If the spool was arranged so that its axis was concentric with the axis of the reflector 20 some of the resistance wire would be closer to the reflector than the rest of the resistance wire. In other words, some of the resistance wire would be in focus with the reflector, some inside the focal point and some 25 outside the focal point, therefore there would be no uniformity of efficiency throughout the heating element, it being borne in mind that in order to obtain the best results all of the resistance wire should 30 be, as nearly as possible, in perfect focus with the reflector.

My invention contemplates two important departures from known types of heaters. First, according to my invention all of the 35 effective part of the resistance wire is presented to some part of the reflector; and second, a convex surface is extended transversely of the axis of the reflector and adjacent the focus thereof, and resistance wire is distributed over such surface, whereby I am enabled 40 to obtain a high degree of efficiency from the heating element, actual tests proving that with the same amount of resistance wire and the same wattage a device 45 constructed in accordance with my invention gives increased heat efficiency over known types, or devices, and that the reflector does not appreciably heat even when the device has been run over a long period.

50 Other features of the invention will be apparent as the details of construction of the invention are better understood, reference being had to the following description in connection with the accompanying drawings, in which

Fig. 1 is a perspective view of a heater

constructed in accordance with my invention.

Fig. 2 is a horizontal, sectional view through the reflector, the heating element 60 being shown in elevation.

Fig. 3 is a perspective view of the heating element, and

Fig. 4 is a sectional view through the heating element.

The reflector 1 may consist of any suitable material. It is preferably metal with a polished surface and it is parabolic in form. The heating element is shown as consisting of a core 2, the exterior of the core 2 being 70 elongated and convexed, that is, the surface of the exterior is curved longitudinally and transversely so that the middle portion 3 of the core is bulged with respect to the end portions. The core 2 is half-round, or substantially so, and it is preferably hollow resembling a miniature trough. The curvature of the core 2, both longitudinally and transversely, is adapted to provide a convex surface facing the concave surface 4 of the 80 reflector 1. The core 2 is supported by the reflector through the medium of two bars 5 and 6 secured to the ends 7 and 8 of the core 2 and to the rim of the reflector 1, there being insulations 9 and 10 between the rim 85 and the members 5 and 6.

The resistance wire is in the form of a coil as indicated at 11. The coil of wire is wound back and forth transversely over the convex face of the core 2 in a series of parallel sections, the several sections being continuous parts of the wire, the wire between each section being looped over the projections 12 on the flat face of the core 2, this being accomplished by forming the loop portions 13 so that they rest against the edges 14 and 15. The ends of the wire indicated at 16 and 17 pass through openings 18 and 19 in the reflector 1, the openings having insulations 20 and 21, and the ends of the 100 wire, 16 and 17, being fastened to the cord 22 in an appropriate manner. For convenience I may utilize a cap 23 to cover the openings and connections and the reflector 1 may be supported in a suitable standard 105 or bracket 24.

It will be seen from the foregoing that all of the effective part of the resistance wire will be presented to the reflector 1, that a portion of the wire will be distributed over 110 a convex surface facing the concave reflector and extending transversely of the

axis thereof, and that the core-supporting means is exterior to the field between the heating element and the reflecting surface.

I prefer to make the core hollow both for lightness and appearance. If it is made of suitable refractory material it can be made thin enough to glow with the wire so as to enhance the appearance of the heater, but this is more or less a minor feature of the invention because the particular material, or the exact configuration of the core, is not the controlling feature of the invention.

What I claim and desire to secure by Letters-Patent is:—

- 15 1. An electric heater, comprising a reflector, a heating element in spaced relation with the reflector, comprising an elongated core half-round in cross section and having a convex inner face curved outwardly from the ends toward the center and faced toward the reflector, and resistance wire on the curved portion of the core.
- 20 2. An electric heater, comprising a reflector, a heating element in spaced relation with the reflector, comprising an elongated

core half-round in cross section and having a convex inner face curved outwardly from the ends toward the center and faced toward the reflector, and resistance wire on the curved portion of the core, the resistance wire running crosswise of the core.

3. An electric heater comprising a reflector, a heating element comprising a core extending transversely of the axis of the reflector, a resistance wire on the side of the core facing the reflector, and supporting means connected with said core exteriorly of the field of projection of rays from the heating element to the reflector.

35 4. An electric heater comprising a reflector, a heating element comprising a core extending transversely of the reflector and resistance wire wound on the side only of the core facing the reflector, and means connected with the core outside of the winding field for supporting the heating element in functional relation to the reflector.

In testimony whereof I affix my signature.

EUGENE E. ANDERSON.
